BAG APPARATUS

Edwin A. Dickmann, Affton, Mo., assignor to Bemis Bro. Bag Company, St. Louis, Mo., a corporation of Missouri

Application August 23, 1956, Serial No. 605,774

8 Claims. (Cl. 1—106)

This invention relates to apparatus for stapling together the two draw-cord legs of a filled draw-cord bag in order to keep the mouth of the bag closed, and more particularly to apparatus of this class wherein filled draw-cord bags are hung by their draw cords on hooks on a conveyor which carries them to a draw-cord stapler adapted automatically to clinch a staple around the two draw-cord legs of each bag adjacent the gathered mouth of the bag.

Prior draw-cord stapling apparatus of the class described has not been wholly satisfactory because of the absence of any provision to compensate for the fact that draw-cord bags, even though of the same size and having the same length of draw cord, may be so differently packed that they hang substantially different distances below the conveyor. For example, in the case of open-mesh ten pound potato bags, a compactly packed bag may hang down below the conveyor a distance of ten inches, while a loosely packed bag in which the contents are not well nested (same length of draw cord and weight of potatoes) may hang down only seven inches. Assuming that the prior apparatus is adjusted to clinch a staple around the draw cord three-fourths of an inch from the gathered mouth of a loosely packed bag, it will then clinch the staple around the draw cord three and three-fourths inches from the gathered mouth of a compactly packed bag. Also, the prior apparatus may impose undue strain on the draw cords, requires manual adjustment to take care of bags of each different size, requires delicate timing adjustment of the stapler for a given speed of the conveyor, and requires change of timing for any change in speed of the conveyor.

Among the several objects of the invention may be noted the provision of an improved draw-cord stapling apparatus of the class described which is adapted to clinch around the two legs of the draw cord of each bag carried by the conveyor a staple close to the gathered mouth of the bag, substantially regardless of the distance which the bag hangs down below the conveyor; the provision of apparatus of the class described which acts without unduly straining the draw cords of the bags; the provision of apparatus of this class which is adapted to apply the staple close to the gathered mouths of bags of a range of sizes (with a range of lengths of draw cord) without any adjustment whatsoever of the apparatus; the provision of apparatus of this class of such construction as to avoid any necessity for delicate timing adjustment of the stapler and also such that the conveyor may be operated at different speeds as desired without requiring any timing adjustment of the stapler; the provision of apparatus of this class which functions to clinch the staple entirely around the two legs of the draw cord and avoids having the staple pierce the draw cord; the provision of apparatus of this class which functions to clinch the staple around the two legs of the draw cord under the condition of no relative motion between the draw-cord legs and the stapling mechanism; and the provision of apparatus of the class described which is of relatively economical construction.

2

and reliable in operation. Other objects and features will be in part apparent and in part pointed out herein-after.

The invention accordingly comprises the constructions hereinafter described, the scope of the invention being indicated in the following claims.

In the accompanying drawings, in which one of various possible embodiments of the invention is illustrated,

Fig. 1 is a view in elevation of an apparatus of this invention as viewed from one side thereof, parts being broken away;

Fig. 2 is a vertical transverse cross section taken on line 2—2 of Fig. 1;

Fig. 3 is an enlarged horizontal section taken on line 3—3 of Fig. 1;

Fig. 4 is an enlarged horizontal section taken on line 4—4 of Fig. 1;

Fig. 5 is an enlarged horizontal section taken on line 5—5 of Fig. 1, showing parts in a position assumed near the end of a cycle of operation;

Fig. 6 is an enlargement of part of Fig. 5, showing parts in a position assumed shortly after the initiation of a cycle of operation; and,

Fig. 7 is a horizontal section taken on line 7—7 of Fig. 1, showing parts in their at-rest position, and with parts broken away.

Corresponding reference characters indicate corresponding parts throughout the several views of the drawings.

Referring to the drawings, first more particularly to Figs. 1 and 2, a draw-cord stapling apparatus of this invention is shown to comprise a main frame generally designated 1 and a vertically adjustable sub-frame generally designated 3. The main frame 1 comprises a pair of posts 5 on pedestals 7 with upper and lower horizontal braces 9 and 11 extending between the posts. The adjustable subframe 3 comprises vertical side members 13 having a horizontal member 15 extending between their lower ends, the side members 13 having sleeves 17 fixed thereon which are slidable on the posts above the upper brace 9. A screw member 19 extends down from the horizontal member 15 through a sleeve 21 rotatable in the upper brace 9. The sleeve 21 has a head 23 on its upper end which bears on a thrust bearing 25. The sleeve is internally threaded and has a hand wheel 27 fixed on its lower end. The arrangement is such that by turning the hand wheel 27 in one direction or the other, the sub-frame 3 may be raised or lowered to different elevations as desired.

At the upper ends of the vertical side members 13 of the sub-frame are cross-bars 29 carrying a pair of tracks 31. A carriage generally designated 33 is hung from these tracks and is movable back and forth in horizontal direction between the side members 13 of the sub-frame. The carriage 33 comprises an upper horizontal plate 35, a lower horizontal plate 37, and four vertical tubular spacer posts 39, one at each corner of the plates. Bolts 41 extend through the tubular posts 39 and have nuts 43 threaded thereon for holding the carriage posts in assembled relation. The bolts, at their upper ends, are fixed to roller members 45 which ride in the tracks 31. The carriage is biased in a rearward direction to a retracted position against a stop 47 on member 15 by a pair of spring means indicated at 49. Each spring means 49, as shown, is simply a conventional commercially available dashpot type spring door check. They are carried by one of the sleeves 17. A screw for adjusting the tension of the spring means is indicated at 51. The screw 51 is rotatable on a shaft 53 (see Fig. 3) extending outward from the stated sleeve 17 and is threaded in

a U-shaped yoke 55 which straddles this sleeve, the rearward ends of the spring means 49 being connected to the

sides of the yoke as indicated at 57. A collar 59 is fixed on the outer end of the shaft.

A draw-cord stapler, generally designated 61, is mounted on the lower carriage plate 37. This stapler is a conventional commercially available draw-cord stapling machine with certain revisions adapting it for use in the present invention. In general, the stapler comprises a housing 63 mounted on the plate 37 on spacer posts 65. It has a vertical camshaft indicated at 67 (see Figs. 5-7). This is adapted to be driven in counterclockwise direction as viewed from above through one revolution on each stapling operation by mechanism including a mechanical clutch indicated at 69. The clutch has a driving member 71 and a driven member 73. The driving member 71 is adapted to be continuously driven by an electric motor 75 via a belt and pulley drive 77. A switch for the motor is indicated at 78 in Fig. 1. The driven member 73 is fixed on a shaft 79 which extends into the stapler housing 63. Fixed on shaft 79 in the housing is a worm 81 in mesh with a worm gear 83 on the camshaft 67.

Means for engaging and disengaging the clutch 69 is shown to comprise a shifter 85 (see Fig. 7). This is biased toward the left as viewed in Fig. 7 by a spring plunger 86. Mechanism for operating the shifter is shown to comprise a solenoid 87 (see Figs. 1, 2 and 5) having its plunger 89 connected by a link 91 to a lever 93 pivoted at 95 in the housing 63. An arm 97 also pivoted at 95 has its end extending into a groove 99 in the shifter. A spring 101 connected to the lever 93 biases the latter to the retracted position shown in Fig. 7. A dog 102 is pivoted on the lever 93 at 103. The dog is biased outward by a spring 104. It has a notch 105 receiving a projection 106 on the arm 97. Fixed on the camshaft 67 within the stapler housing is a small shifter control cam 107. This engages a follower 109 on one end of a shifter control lever 111 pivoted at 113 on the bottom of the stapler housing 63 and having a pin 115 at its other end extending into a groove 117 in the shifter 85.

The above described arrangement is such that when the solenoid 87 is energized, lever 93 is swung clockwise from its retracted position as viewed in Fig. 7. The dog 102 carried by lever 93 engages the projection 106 on arm 97 and swings arm 97 clockwise as viewed in Fig. 7 to move the shifter 85 toward the right as viewed in Fig. 7. This engages the clutch 69 and initiates a stapling cycle. Upon the movement of the shifter to the right, lever 111 is swung counterclockwise to move the follower 109 away from the cam 107. The shifter control cam 107 is developed and phased so that in response to deenergization of the solenoid 87 and one revolution of the cam 107, the shifter 85 is returned to its retracted Fig. 7 position. For this purpose, the cam is adapted to hold the lever 111 from rotating clockwise for an interval after deenergization of the solenoid, then to release the lever 111 to allow it to rotate clockwise so that the shifter may return leftward to its retracted position.

Mounted on the stapler housing 63 is a head indicated at 119. The head 119 carries a clincher block 121 pivoted at 123 for swinging movement on a vertical axis, and conventional mechanism indicated generally at 125 for feeding a flat wire W, cutting the wire into staple lengths, and forming each length into a staple and driving it against the clincher block 121. Fixed on the upper end of camshaft 67 above the housing is a large stapler control cam 127. This engages a follower roller 129 on a lever 131 pivoted at 133 and connected by a link 135 to the clincher block for operating the clincher block. A return spring for lever 131 is indicated at 136. Pivoted at 137 on the cam 127 is a bell crank lever 139 having one end connected at 140 to a slide 141 for operating the wire feeding, cutting, forming and driving mechanism 75

125. The other end of the bell crank lever is connected by a link 143 to a gathering arm 145 pivoted at 147.

Guides 149 and 151 mounted on the carriage 33 define a draw-cord guide passage 153. The guide 149 is constituted by a plate mounted on the stapler housing 63. The guide 151 is constituted by a plate adjustably mounted as indicated at 155 on a supporting plate 157. The latter is mounted at the lower end of one leg of a cantilever frame 159 of inverted J-shape, the other (and shorter) leg of the frame 159 being mounted on the upper carriage plate 35. The rearward ends of the guide plates 149 and 151 are angled upward as appears in Figs. 1 and 2. The guide plates 149 and 151 have opposed edges 161 and 163 shaped so that the guide passage 153 has a tapering entrance throat 165 (see Fig. 5), a straight portion 167, a portion 169 curving around on the outside of the arcuate path of the outer end of the gathering arm 145, a portion 171 curving back into the arcuate path of the outer end of the gathering arm, and an exit portion 173 curving outward from the forward end of portion 171. The clincher block 121 is rotatable on its pivot 123 between the clinching position shown in Fig. 6 and the retracted position shown in Fig. 5. In the clinching position, it blocks the draw-cord guide passage 153 at the forward end of the portion 171 of the passage. In the retracted position, it is clear of the guide passage. The cam 127 is developed and phased so that the clincher block 121 occupies its clinching position between stapling cycles.

At 175 is indicated a portion of an endless conveyor for conveying filled draw-cord bags B to the stapler 61 for applying staples S to the draw cords and for conveying the bags away from the stapler after stapling. The conveyor (which is conventional) comprises an endless chain 179 riding in a track 181. Secured to the chain at spaced intervals are brackets 183. A hook 185 hangs down from each bracket. The chain is continuously driven by suitable means (not shown) in the direction from right to left as viewed in Fig. 1. Also as shown in Fig. 1, a filled draw-cord bag B is hung by its draw cord D on each of the hooks 185. Different bags may hang down different distances below the hooks, due to variations in packing bags of the same size, and due to bags of a range of sizes being packed simultaneously and interspersed at random on successive hooks 185.

The chain 179 travels in a vertical plane slightly offset toward the left as viewed in Fig. 2 with respect to the straight portion 167 of the cord guide passage 153 above the guides 149, 151, so that the draw cord of each bag will ride the edge 161 of guide 149. The sub-frame 3 is vertically adjusted by turning hand wheel 27 so that the guides 149, 151 are located below the hooks a distance less than the shortest hanging distance to be expected. The arrangement is such that the two legs of the draw cord D of a bag travelling from right to left as viewed in Fig. 1 enter the guide passage 153, are guided around the outer end of the gathering arm 145 (which is retracted at this time as will appear) and then engage the clincher block 121 (which is in clinching position). The engagement of the two legs of the draw cord with the clincher block results, upon the continued movement of the bag and its draw cord by the conveyor, in the movement of the carriage 33 from right to left as viewed in Fig. 1 against the return bias of the spring means 49.

The above-stated movement of the carriage is utilized to initiate operation of the stapler 61 through a stapling cycle. For this purpose, there is provided a carriage-operated control switch 187 for the solenoid 87. This switch 187 is suspended from one of the tracks 31 as indicated at 189 and is adapted to move back and forth in the direction of the length of this track. The switch has an operating arm 191 (see Figs. 1 and 4) lightly biased by a switch spring (not shown) to a retracted, circuit-breaking position. An operating member 193 for the

arm 191 is suspended from the stated track 31 and is adapted to move back and forth in the direction of the length of the track. At 195 is indicated a connection between member 193 and the adjacent carriage bolt 41. A lost-motion link 197 (see Fig. 4) connects the member 193 and the switch suspension 189. The arrangement is such that upon movement of the carriage 33 toward the left from its retracted position shown in Fig. 1, the member 193 is moved toward the left to operate the switch arm 191 to close the switch. The frictional resistance to movement of the switch is sufficient to hold the switch against movement to the left until the member 193 overcomes the light spring bias on the switch arm 191. The lost-motion link 197 permits the relative movement between member 193 and the switch required to operate the switch arm. Then upon continued movement of the carriage toward the left, the switch moves with the carriage. Upon the return of the carriage toward the right to retracted position, the lost-motion link 197 permits the member 193 to move away from the switch so that the switch opens, and then the switch moves back with the carriage.

The sub-frame 3 carries a platform 199 having an upwardly inclined portion 201 up which the filled bags travel as they approach the stapler and a downwardly inclined portion 203 down which the bags travel as they leave the stapler. This partially relieves the draw cords of tension during stapling. The motor 75 is mounted on a platform 205 which extends across the tracks 31. There is sufficient play in the belt of the drive 77 to allow the necessary movement of the carriage. The wire W is drawn from a spool 207 carried at the lower end of a vertical rod 209 extending down from the platform 205. Having the motor 75 and spool 207 mounted as described withdraws their inertia (which is substantial) from the carriage 33.

Operation is as follows:

Filled bags B are hung by their draw cords D on the hooks of the conveyor at a station ahead of the stapling apparatus. The bags are moved by the conveyor from right to left as illustrated in Fig. 1. As a given bag moves along, the two legs of its draw cord D enter the throat 165 of the draw-cord guide passage 153 and travel through the straight portion 167 of this passage along the edge 161 of guide plate 149, through the curved portion 169 of the passage around the outer end of the gathering arm 145, and into engagement with the clincher block 121. Prior to the time the draw-cord legs enter the throat 165 of passage 153, the bag comes into engagement with the portion 201 of the platform 109, and slides up this portion of the platform. This partially relieves the draw cord of the tension caused by the weight of the filled bag. Engagement of the draw-cord legs with the clincher block 121 and continued movement of the bag by the conveyor results in movement of the carriage 33 in the same direction and speed as the bag (from right to left as viewed in Fig. 1) against the bias of the spring return means 49. This bias is adjusted so that movement of the carriage does not occur, however, until the draw-cord legs, after first coming into engagement with the clincher block 121, are pulled forward and upward by the conveyor through the guide passage 153 to a point where the gathered mouth of the bag is a short distance (three-fourths of an inch, for example) below the clincher block 121.

Upon the stated movement of the carriage, the switch 187 is closed in response to carriage movement, and solenoid 87 is energized to rock the lever 93 clockwise as viewed in Fig. 7. The dog 102 on lever 93 engages projection 106 on arm 97 and rocks arm 97 clockwise as viewed in Fig. 7 to move the shifter 85 to the right as viewed in Fig. 7. This engages the clutch 69 to drive the shaft 79. It also swings lever 111 counterclockwise from its Fig. 7 position. Shaft 79, via gearing 81, 83 drives the camshaft 67 counterclockwise as viewed in

Fig. 7. Upon rotation of the camshaft 67 and cams 107 and 127 carried thereby, the pivot 137 on cam 127 for bell crank lever 139 is rotated around the camshaft axis. The bell crank lever 139 thereupon acts through the link 143 to swing the gathering arm 145 counterclockwise on its pivot 147 from its retracted position illustrated in Fig. 7 and the end of the gathering arm engages the two draw-cord legs and holds them, bunched together, firmly against the clincher block 121. The bell crank lever 139 also acts to move the slide 141 for operating the wire feeding, cutting, forming and driving mechanism 125. This mechanism, as will be understood, acts to cut off a length of the wire, form it into a U-shaped staple, and drive the staple against the clincher block to clinch the staple around the two draw-cord legs. The driving of the staple occurs after the gathering arm has acted to hold the draw-cord legs firmly against the clincher block, there then being no relative motion between the draw-cord legs and the clincher block.

Following the driving of the staple, the cam 127 acts to allow the movement of the clincher block 121 to the retracted position shown in Fig. 5 under the bias of the spring 136. This frees the draw-cord legs, upon which the stapling operation has been completed, for travel out through the exit portion 173 of the guide passage 153. It also frees the carriage 33 for return to its retracted position under the bias of the spring return means 49. Here it will be understood that the carriage has been moving forward throughout the stapling cycle from the time the draw-cord legs have been pulled upward and forward past the clincher block to a point where the gathered mouth of the bag is a short distance below the clincher block until the clincher block is retracted. The switch 187 opens during the initial phase of the return movement of the carriage 33, and the solenoid 87 is deenergized. Subsequently, cam 107 reaches a position allowing lever 111 to swing clockwise, and the spring means 86 acts to move the shifter 85 back to the left to disengage the clutch 69. This occurs upon completion of one revolution of the camshaft 67. When the clutch disengages, the cam 127 and bell crank lever reach their initial position shown in Fig. 7, the gathering arm 145 and the slide 141 are returned to their retracted position shown in Fig. 7, and the clincher block 121 is returned to its clinching, passage-blocking position in readiness for the stapling of the draw-cord legs of the next bag.

It will be understood that the term "draw cord" is intended to include the various types of materials used in draw-closure bags, such as strand material, tape (including woven tape), and the like. The apparatus of this invention is useful for stapling both open-mesh draw-cord bags and plastic draw-cord bags. It will be apparent that it operates to clinch a staple S around the two legs of draw cord D of each bag B carried by the conveyor close to the gathered mouth of the bag regardless of the distance which the bag hangs down below the conveyor because the draw-cord legs are pulled against the clincher block 121 to bring the gathered mouth of the bag a short distance from the clincher block before a stapling cycle is initiated. For the same reason, no adjustment whatsoever of the apparatus is required to accommodate a range of sizes of bags (with a range of lengths of draw cord) to obtain stapling close to the bag mouth, and no major adjustment is required for a different range of sizes of bags. The only adjustments which may be needed are vertical adjustment of the sub-frame 3 and adjustment of the tension of spring means 49. Stapling takes place without undue strain on the draw cords because the bags are partially supported by the platform 199. No delicate timing adjustment of the stapler is needed and no change in adjustment of timing is required for different conveyor speeds since the stapling cycle is not initiated until the draw-cord legs are in engagement with, and stationary relative to, the clincher block. With the draw-cord guide passage shaped as

shown, and located so that the draw-cord legs ride the edge of the passage toward the stapler, the draw-cord legs are held by the gathering arm during the actual stapling in proper position for clinching of the staple around the two legs of the cord without piercing either leg of the cord. The curved portion 169 of the draw-cord passage permits the draw-cord legs of the bag following the one which has just been stapled to move freely in the passage without interference from the gathering arm 145 while it is returning to retracted position.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

I claim:

1. Apparatus for stapling the draw cords of filled draw-cord bags hung by their draw cords from a conveyor, said bags travelling with the conveyor in a predetermined path, comprising a stapler mounted for movement away from a retracted position in the direction of travel of the bags, said stapler having a clincher block movable between a clinching position and a retracted position, said clincher block normally occupying its clinching position, said stapler being movable away from its retracted position by engagement with the clincher block of the two legs of the draw cord of each bag travelling with the conveyor, and means responsive to movement of the stapler away from retracted position for effecting operation of the stapler through a cycle in which it acts to clinch a staple against the clincher block around the two legs of the draw cord in engagement with the block, then acts to retract the block to allow the stapler to return to retracted position, and then acts to return the clincher block to clinching position.

2. Apparatus for stapling the draw cords of filled draw-cord bags hung by their draw cords from a conveyor, said bags travelling with the conveyor in a predetermined path, comprising a stapler mounted for movement away from a retracted position in the direction of travel of the bags and biased to return to retracted position, said stapler having a clincher block movable between a clinching position and a retracted position, said clincher block normally occupying its clinching position, said stapler being movable away from its retracted position by engagement with the clincher block of the two legs of the draw cord of each bag travelling with the conveyor, electrical means for controlling the operation of the stapler including a switch, and means responsive to movement of the stapler away from retracted position for operating the switch to effect operation of the stapler through a cycle in which it acts to clinch a staple against the clincher block around the two legs of the draw cord in engagement with the block, then acts to retract the block to allow the stapler to return to retracted position under the stated bias, and then acts to return the clincher block to clinching position.

3. Apparatus as set forth in claim 2 wherein means is provided for operating the switch upon the initial movement of the stapler away from retracted position and then for moving the switch with the carriage.

4. Apparatus for stapling the draw cords of filled draw-cord bags hung by their draw cords from a conveyor, said bags travelling with the conveyor in a predetermined path, comprising a carriage mounted for movement away from a retracted position in the direction of travel of the bags, means carried by the carriage defining a guide passage for the draw cords, the two legs of the draw cord of each bag travelling with the conveyor being adapted to enter and travel through the guide passage, a stapler carried by the carriage having a clincher block movable between a clinching position in which it blocks the guide passage and a retracted position clear of the guide passage,

said clincher block normally occupying its clinching, passage-blocking position, said carriage being movable away from its retracted position by engagement with the clincher block of the two legs of the draw cord of each bag travelling with the conveyor, and means responsive to movement of the carriage away from retracted position for effecting operation of the stapler through a cycle in which it acts to clinch a staple against the clincher block around the two legs of the draw cord in engagement with the block, then acts to retract the block to allow the stapled draw cord to pass out of the passage and to allow the carriage to return to retracted position, and then acts to return the clincher block to its clinching, passage-blocking position.

5. Apparatus for stapling the draw cords of filled draw-cord bags hung by their draw cords from a conveyor, said bags travelling with the conveyor in a predetermined path, comprising a carriage mounted for movement away from a retracted position in the direction of travel of the bags and biased to return to retracted position, means carried by the carriage defining a guide passage for the draw cords, the two legs of the draw cord of each bag travelling with the conveyor being adapted to enter and travel through the guide passage, a stapler carried by the carriage having a clincher block movable between a clinching position in which it blocks the guide passage and a retracted position clear of the guide passage, said clincher block normally occupying its clinching, passage-blocking position, said carriage being movable away from its retracted position by engagement with the clinching block of the two legs of the draw cord of each bag travelling with the conveyor, electrical means for controlling the operation of the stapler including a switch, and means responsive to movement of the carriage away from retracted position for operating the switch to effect operation of the stapler through a cycle in which it acts to clinch a staple against the clincher block around the two legs of the draw cord in engagement with the block, then acts to retract the block to allow the stapled draw cord to pass out of the passage and to allow the carriage to return to retracted position, and then acts to return the clincher block to its clinching, passage-blocking position.

6. Apparatus as set forth in claim 5 wherein the switch is mounted for movement away from a retracted position in the direction of travel of the bags, and wherein means is provided for closing the switch upon the initial movement of the carriage away from retracted position and then for moving the closed switch with the carriage, and for opening the switch upon the initial return movement of the carriage and then for moving the switch back to its retracted position.

7. Apparatus for stapling the draw cords of filled draw-cord bags hung by their draw cords from a conveyor, said bags travelling with the conveyor in a predetermined path, comprising a stapler mounted for movement away from a retracted position in the direction of travel of the bags, said stapler having a clincher block movable between a clinching position and a retracted position, said clincher block normally occupying its clinching position, said stapler having a draw-cord gathering arm movable from a retracted position toward the clincher block, means for guiding the two legs of a draw cord around the end of the retracted gathering arm, said stapler being movable away from its retracted position by engagement with the clincher block of the two legs of the draw cord of each bag travelling with the conveyor, and means responsive to movement of the stapler away from retracted position for effecting operation of the stapler through a cycle in which it acts to move the gathering arm toward the clincher block, then acts to clinch a staple against the block around the two legs of the draw cord in engagement with the block, then acts to retract the block to allow the stapler to return to retracted position, and then acts to return the gathering arm to

retracted position and the clincher block to clinching position.

8. Apparatus for stapling the draw cords of filled draw-cord bags hung by their draw cords from a conveyor, said bags travelling with the conveyor in a predetermined path, comprising a carriage mounted for movement away from a retracted position in the direction of travel of the bags, means carried by the carriage defining a guide passage for the draw cords, the two legs of the draw cord of each bag travelling with the conveyor being adapted to enter and travel through the guide passage, a stapler carried by the carriage having a clincher block movable between a clinching position in which it blocks the guide passage and a retracted position clear of the guide passage, said clincher block normally occupying its clinching, passage-blocking position, said stapler having a draw-cord gathering arm movable from a retracted position toward the clincher block, said guide passage having a

portion curved around the end of the retracted gathering arm, said carriage being movable away from its retracted position by engagement with the clincher block of the two legs of the draw cord of each bag travelling with the conveyor, and means responsive to movement of the carriage away from retracted position for effecting operation of the stapler through a cycle in which it acts to move the gathering arm toward the clincher block, then acts to clinch a staple against the block around the two legs of the draw cord in engagement with the block, then acts to retract the block to allow the stapled draw cord to pass out of the passage and to allow the carriage to return to retracted position, and then acts to return the gathering arm to retracted position and the clincher block to its clinching, passage-blocking position.
